ICE CARRYING BAG

Ross R. Rockwell, Binghamton, N. Y.

Application February 6, 1936, Serial No. 62,703

1 Claim. (Cl. 224—45)

My invention relates to improvements in ice carrying bags.

It has long been a serious problem in the delivery of ice to refrigerators, particularly from the well known ice truck to the refrigerator of a dwelling house, to prevent the dripping of water from the cake of ice on the floor and also the marring of the refrigerators or ice boxes during the transfer of the cake of ice from the carrier to the ice compartment of the box. By my invention I have provided a carrier bag by means of which a cake of ice can be easily and readily transported from the truck to the refrigerator without dripping water therefrom and which serves as a protecting means during the transfer of the cake of ice to the ice compartment of the refrigerator so as not to mar or scratch the box. This comprises the principal object of my invention.

Another object lies in the provision of means whereby the cake of ice is carriable within the bag by the usual ice tongs.

Still another object lies in the provision of means for trapping the water which drips from the cake of ice, and retaining it in a special compartment of the bag during transportation and delivery of the ice to the ice box.

Another object lies in the provision of means whereby the bag when not in use can be hung up in such manner that the trapped water can drain from the special compartment back into the bag for ready ejection prior to the next use thereof.

Still another object lies in the provision of reinforcing means for the bag whereby the same is of durable construction and leak-tight.

A further object lies in the provision of means on the bag for retaining a cake of ice therein during transportation.

Other objects and advantages will appear as the description proceeds, reference now being had to the figures of the accompanying drawing forming a part of this application and wherein like reference numerals indicate like parts.

In the drawing:

Figure 1 is a perspective view of a carrying bag embodying my invention.

Figure 2 is a detail sectional view taken on the line 2—2 of Figure 1 illustrating the water trap of the bag.

Figure 3 is a detail sectional view illustrating a feature of the trap.

Figure 4 is a detail sectional view taken on the line 4—4 of Figure 1, illustrating the corner construction of the bag.

The reference character 1 refers generally to the bag in its entirety and which is preferably of substantially rectangular form. The bag is made of any suitable material, but heavy canvas has proven probably the most effective for the purpose inasmuch as it is relatively light in weight, durable, and waterproof.

The bag is formed with a bottom 2, side walls 3, an upper end 4, and a lower end 5, and as shown in Figure 1 is open opposite the bottom 2 to receive a cake of ice to be transported therein. The lower end 5 of the bag has an extending portion 6 overlying the lower end of the open side of the bag for a short distance which serves as a flange retaining means for a cake of ice placed in the bag and allowed to rest upon the lower end 5 during transportation. Obviously this flange 6 overlies the lower end of the cake of ice and prevents its inadvertent displacement and also prevents water dripping therefrom out of the bag due to the pocket-like arrangement at the lower end of the bag produced by this flange.

The two side walls 3 of the bag are provided at points substantially spaced from the open side and adjacent the upper end of the bag with openings 7 through which the ordinary ice carrying tongs are adapted to pass and engage the cake of ice within the bag for carrying. In practice, the tongs engage over the upper end 4, around the sides 3 and through the openings 7 and the bag with the cake of ice therein thus engaged may be swung over the back of the carrier or carried in any other manner with the lower end 5 with its pocket-like construction, due to the flange 6, on the bottom.

The edges of the openings 7 are preferably reinforced as at 8 by rope or other suitable material so as to prevent tearing and to increase the life of the bag. Inside the bag there are provided reinforcing members 9 of leather or the like sewed, riveted, or otherwise secured at points directly adjacent the openings 7 and extending from such openings to the bottom 2 and outwardly on such bottom for a substantial distance. This provides a serviceable reinforcement directly adjacent the points where the bag with its load of ice is supported by the ice tongs.

The edge of the bag surrounding the open side thereof is reinforced as at 10 by rope or the like preferably sewed or otherwise secured within the free edge of the canvas formed therearound. This feature coupled with the spacing of the openings 7, substantially below the open edge provides adequate protective means against

marring the refrigerator when the ice cake is transferred from the bag into the ice compartment thereof. It will be clear that with the ice tongs swung to a position below the bottom 2, the bag with its cake of ice may be placed directly over and adjacent the ice compartment opening of the refrigerator with the reinforced edge 10 of the bag engaging directly thereagainst and the ice transferred into the ice box with little danger of the ice tongs or any other rigid element engaging against the ice box. This is particularly true of and useful in connection with ice boxes having the opening to the ice compartment on the top. This is an important feature inasmuch as it eliminates the annoyance and expense attendant upon filling ice boxes with cakes of ice by the ordinary means of carriers.

The corners of my improved bag are provided with special reinforcing means shown clearly in Figure 4 and which consist of lengths of rope 11 or the like extending along the corner and around which is folded the end of the canvas material as shown at 12, the end of the adjacent end or side being then sewed or otherwise suitably secured to the end of the encircling material as at 13, all adjacent laminations being firmly secured together. This not only provides a strongly reinforced corner structure but eliminates any element which might scratch the ice box and in addition, provides an adequate waterproof or leak-tight construction.

On the inside of the bag and at each corner there is provided an additional reinforcing member 14 in the form of leather or the like which may be sewed or otherwise secured in position and which further reinforces the corner upon which there is naturally strain due to the lifting of the bag loaded with ice.

As an additional reinforcement there may be provided inside the bag and completely around the same directly adjacent the bottom 2 and extending upwardly a short distance on the upper end member 4, the side walls 3 and the lower end member 5, a strip of leather or the like 15, which directly engages against the ice in the bag and takes the strain thereof from the canvas walls.

The lower end wall 5 of the bag, against which the cake of ice normally rests in the carrying position of the bag, is provided with an additional reinforcement in the form of a rope 16 extending from a point centrally of the outer edge of such lower wall, namely, directly adjacent the flange 6, divergently to the opposite corners of such wall 5, as shown clearly in Figure 1.

On the outside of the lower end member 5 and also of the upper end member 4, there are provided suitable handles 17 by means of which the bag may be readily carried by hand if the ice tongs are not used in the manner heretofore described.

The adjacent edges of the lower end member 5 and the bottom 2 are not joined together but extend outwardly away from this end of the bag for a substantial distance as shown clearly in Figures 1 and 2, to form a pocket or trap for water as it may drip from the ice in the bag. In the form shown, the lower end member 5 and the bottom 2, and for that matter the end member 4, are formed of one piece of material which lends itself readily to the formation of the pocket 18, one side of the pocket being provided by the extension 5a of the end 5, and the other side of the pocket by the extension 2a of the bottom 2. The side edges of the extensions 5a and 2a are suitably

secured together as by sewing or the like in a leak-proof manner. A reinforcing strip 19 may be provided over the extension 5a adjacent the lower end 5 of the bag and this may be comprised of leather, heavy canvas or the like. An additional reinforcing means is provided inside the pocket 18 as by a strip 20 of canvas or the like which may act as a lining for the pocket and extending from a point 21 adjacent the lower edge of the end 5 around the pocket and back for a substantial distance over the bottom 2, as shown clearly in Figure 2. If desired this reinforcement strip 20 may extend entirely across the bottom 2 forming a double fold therefor.

An inner lining member 22 is provided for the pocket 18 also extending from a point adjacent the lower edge of the end 5 completely around the inside of the pocket and to a point on the bottom 2 substantially opposite the end 5. This lining is preferably made of rubber or the like and adds to the leak-proof character of the pocket.

Obviously the edges of these reinforcing strips and linings are secured together in any suitable manner.

The open end or mouth of the pocket 18 is closed by a strip 23 of metal, hard rubber or other suitable material, extending from the ends of the pocket, that is, from the lower corners of the bag, to a central point within the mouth of the pocket spaced slightly below the end wall 5 to provide converging portions of a trough or guide to such central point whereby water draining from the ice will run to such central point. Spaced slightly from the guide trough 23 is a similar guide trough 24 diverging from a central point in the pocket 18 to the side edges of such pocket in the opposite direction from the trough 23. Openings are provided centrally of the troughs 23 and 24 and communicating with such openings and connecting the troughs 23 and 24, is a hollow tube 25 through which the water drains from the bag into the pocket 18 and likewise through which the water drains out of the pocket 18 back into the bag when the same is not in use.

As shown clearly in Figure 3 there is provided inside the tube 25 a baffle member 26 bent upwardly from a point on the bottom of the tube to a point substantially across the interior diameter of the tube. The purpose of this baffle is to prevent the return of water from the pocket 18 into the bag unless the bag is hung up in a position in which the lower end 5 is on top and in which position it is desired and intended that the water in the pocket shall drain back from the pocket into the bag, namely, between times when the bag is being used for transporting ice. In other words, if during the use of the bag it should be set down for a time on the bottom 2, any water which has previously collected in the pocket 18 will be prevented from running back into the bag by means of the baffle 26 so that when the bag with the ice in it is again picked up for insertion in an ice box, such water will not drip out.

The pocket 18 is provided on its outside with a handle member 27 by means of which the bag can be hung up in the truck or on a wall with the pocket 18 and the lower end 5 uppermost and in which position the water will readily drain from the pocket back into the bag from which it can be easily emptied before loading with ice for the next use.

Straps 28 may be provided exteriorly of the bag as shown in Figure 1, by means of which the

receptacle can be carried on the back of a user, the straps engaging around the shoulders of the user.

It will be understood, of course, that my improved bag can be made in any desired size and of any preferred material. Likewise many changes may be made in details of construction and arrangement of parts without departing from the spirit and scope of my invention. I do not limit myself, therefore, to the exact form herein shown and described other than by the appended claim.

I claim:

An ice delivery receptacle of flexible material comprising a body of substantially rectangular shape and of a depth to substantially confine

therin a block of ice and having one face open and normally disposed uppermost when carrying the block of ice, said body having opposed side walls each having a reinforced opening arranged to permit the ice tongs to extend through the 5 body of the receptacle for gripping the block of ice with the tongs disposed either vertically for carrying the ice and body in a suspended position or disposed horizontally for steadyng the body when being carried on a shoulder of a person and eliminate drip from the melting ice, and a drainage pocket associated with one of the closed sides of the receptacle to accommodate the water occasioned by the melting of the ice.
